UNITED STATES PATENT OFFICE.

WILLIAM E. FISHER, OF MILLER, NEBRASKA.

DELIVERY APPARATUS FOR MAIL OR THE LIKE.

1,130,721.

Specification of Letters Patent.

Patented Mar. 9, 1915.

Application filed July 6, 1914. Serial No. 849,343.

To all whom it may concern:

Be it known that I, WILLIAM E. FISHER, a citizen of the United States, residing at Miller, in the county of Buffalo and State of Nebraska, have invented certain new and useful Improvements in Delivery Apparatus for Mail or the like, of which the following is a specification, reference being had to the accompanying drawings.

10 This invention relates to certain improvements in delivery apparatus for mail or the like and has relation more particularly to a self-propelled mail car designed more particularly for use in rural free delivery systems 15 in which the car is adapted to travel back and forth on an aerial line between a road, traveled by the mail carrier, and a residence or farm house more or less remote therefrom.

Furthermore, the invention has for its object to 20 provide a device of this general character having novel and improved means wherein the power for propelling the car is derived from the force of the wind and wherein the propeller, included in the operating 25 mechanism, is so supported as to be automatically adjusted in accordance with the direction of the wind in order that the best results may be obtained.

The invention also has for its object to 30 provide a device of this general character including novel and improved means whereby the propeller, included in the operating mechanism for the car, is automatically caused to become inoperative when the 35 proper destination has been reached and in such instances during the travel of the car when the wind reaches too great a velocity.

It is also an object of the invention to provide a device of this general character having 40 novel and improved means whereby the possibility of the car dropping to the ground is substantially entirely eliminated in such instances when the supporting wheel may be disengaged from the aerial track-way.

45 A still further object of the invention is to provide a device of this general character including novel and improved means whereby the mail car may be caused to travel in a given direction upon its supporting track-way irrespective of the direction in which the wind may blow.

The invention consists in the details of construction and in the combination and arrangement of the several parts of my im-

proved device whereby certain important 55 advantages are attained and the device is rendered simpler, less expensive and otherwise more convenient and advantageous for use, all as will be hereinafter more fully set forth.

60 The novel features of the invention will be carefully defined in the appended claims.

In order that my invention may be the better understood, I will now proceed to describe the same with reference to the accompanying drawings, wherein—

Figure 1 is a view in perspective of a mail carrying apparatus constructed in accordance with an embodiment of my invention; Fig. 2 is an enlarged fragmentary view, in 70 elevation, illustrating in detail one of the rigid track members herein employed a concomitant part being indicated by dotted lines; Fig. 3 is a view in top plan of the device as illustrated in Fig. 2, with the part 75 shown in dotted lines in Fig. 2 in full lines; Fig. 4 is an elevational view of the opposite rigid track member, herein embodied, and the coacting releasing means; Fig. 5 is a view in top plan of the device as disclosed 80 in Fig. 4; Fig. 6 is an enlarged elevational view, illustrating the means, herein embodied, for propelling the carrier; Fig. 7 is a view, partly in elevation and partly in section, of the controlling mechanism for the 85 propelling means; Fig. 8 is a view, partly in section and partly in elevation, illustrating in detail the member coacting with the structure illustrated in Fig. 7; Fig. 9 is a face view of the tripping member coacting 90 with the hanger as herein set forth; Fig. 10 is a sectional view taken substantially on the line 10—10 of Fig. 6; Fig. 11 is a sectional view taken substantially on the line 11—11 of Fig. 6; and Fig. 12 is an enlarged detail 95 view, partly in elevation and partly in section, illustrating the manner whereby the aerial track way is operatively engaged by a supporting member.

As disclosed in the accompanying drawings, 100 1 and 2 denote, respectively, the house and road terminal supports for the aerial track-way 3, herein disclosed as a cable, such cable being supported intermediate its length by one or more brackets 4 secured to 105 an upstanding post 5. As herein embodied, the bracket 4 has its outer extremity terminating in an upstanding projection 6 having

its upper face concaved and provided with the open slot 7. The portion of the track-way resting upon the concaved face of the upstanding projection 6 is surrounded by 5 the metallic ferrule 8, the free ends whereof being disposed in the open slot 7 and operatively engaged by a rivet 9 or the like disposed through said upstanding projection 6 and the free end portion of the ferrule 8 10 within the open slot 7, as is believed to be particularly shown in the accompanying drawings.

In practice, I find it of advantage to have the terminal support 1 comprise an upright post suitably anchored, and the opposite terminal support 2 comprise a substantially U- 15 shape frame member formed preferably of gas pipe and disposed on an outward and upward incline so that the space 10 may be 20 so engaged with the anchor 11 as to create the requisite tension upon the track-way 3.

As herein disclosed, the bracket 4 is substantially L-shape in form with the foot 12 thereof in contact with an adjacent face 25 of the post 5 and having directed through its free extremity the anchoring member 14 which may be a conventional bolt or the like, while the inner extremity of the foot is straddled by the strap 15, the extremities 30 whereof being suitably anchored in any conventional way to the post 5. I find it of particular advantage to employ the strap 15 in order to avoid weakening of the bracket 4 by the passing of anchoring means there- 35 through, as is believed to be self-evident.

The opposite extremities of the track-way or cable 3 are secured to the rigid track members 16 having produced intermediate their lengths the depressions 17 for a purpose to be hereinafter more particularly referred to, and each of these rigid track members 16 is secured to the respective terminal supports 1 and 2, the connection between the support 1 and the adjacent rigid track member 16 being of such a character as to permit an adjustment of the member 16 relative to the support in order to provide further means for controlling the tension of the track-way. I also find it of advantage to 40 interpose in the track-way 3 a coil section 45 50 55 60 65 70 75 80 85 90 95 100 105 110 115 120 125 130 135 140 145 150 155 160 165 170 175 180 185 190 195 200 205 struction and material, I prefer to employ conventional helical springs.

Slidably keyed to the shaft member 33 is a clutch member 47 having produced in its face adjacent the lever 44 the spaced recesses or cavities 48 adapted to receive the projection 49 carried by the lever 44, it being readily perceived that when such projection 49 is positioned within one of the recesses or cavities 48, the shaft 33 will be caused to rotate with the face gear 43 and the hub 37. It will also be observed that the cavities or recesses 48 are so relatively spaced as to reverse the hand of the blades 39 relative to the direction of rotation, as is believed to be clearly apparent to those skilled in the art to which my present invention appertains.

By the use of the expandable members 46, it will be readily perceived that an automatic governing means is provided. The normal tension of the members 46 is to cause rotation of the shaft 33 with the face gear 43 during a moderate velocity of the wind, but should such velocity become excessive, it will be perceived that the members 46 will readily permit the blades 39 to assume a substantially neutral position.

Proper coaction between the clutch member 47 and the lever 44, or more particularly the projection 49 thereof, is maintained through the medium of the expandable member 50, herein disclosed as a coil spring surrounding the shaft 33 and interposed between the inner face of the clutch member 47 and a washer 51 or the like embracing the shaft 33 in close proximity to the outer extremity of the tubular arm 34.

Suitably secured to the hanger 24 above the sleeve 30 is the depending arm 52 suitably curved to overlie the sleeve 30 and projecting outwardly from the lower or free extremity of such arm are the studs 53 disposed through the longitudinally disposed elongated slots 54 produced in the strap 55, the upper extremity 56 whereof is angularly disposed at substantially right angles, while the lower extremity has secured thereto the lug 57 in substantial parallelism with the extremity 56. The strap 55 is adapted to be moved freely relative to the arm 54 and has its lower end portion projected through a loop 58 surrounding the sleeve 30 and formed on the free extremity of the horizontal stem of a bell lever 59 pivotally engaged, as at 60, to a bracket 61 projecting upwardly from the tubular arm 34. The depending stem of the bell lever 59 terminates in a yoke 62 suitably coacting with the clutch member 47 whereby it will be readily perceived that upward movement of the strap 55 will result in the clutch member 47 being adjusted into an inoperative position.

The rigid track members 16 have suitably secured thereto the extremities of the

elongated striker arms 63, the free extremities whereof being spaced a predetermined distance relative to the track member and intersecting the depression 17. The extremity 56 is adapted to engage the striker 70 arm 63 when the supporting wheel 26 drops within the depression or gap 17, whereby it will be readily perceived that the requisite upward movement will be imparted to the strap 55.

In order that the supporting wheel 26 may be readily and conveniently raised from within the gap 17 of the track member 16 operatively engaged with the terminal support 2, I have the gap or depression 17 thereof intersected by the pivotally connected links 64, one of such links being pivotally engaged with the track member 16 adjacent the inner end thereof, while the opposite end link is engaged by the flexible member 65, herein disclosed as a linked chain disposed upwardly and around a pulley 66 mounted in the upper extremity of an arm 67 projecting upwardly and forwardly from the terminal support 2 and terminating at a point within convenient reach of the postman so that he can operate the links with convenience and facility. It is also to be noted that the postman properly manipulates the lever 44 so that the car or box 19 will travel in the proper direction. It is also to be observed that the supporting wheel 26 rides over and upon the links 64, as is believed to be clearly apparent in the accompanying drawings, and for this reason the link pivotally engaged with the track member 16 comprises spaced parallel members, as is believed to be obvious.

In order that the tubular arm 34 may automatically adjust itself relative to the direction from which the wind blows so that the propeller blades 39 may properly rotate, I find it of advantage to secure to a side of the tubular arm 34 the blade 67, preferably rectangular in form and of predetermined dimensions.

If, from any cause, the car or box 19 should fail to travel upon the aerial trackway 3, I find it of advantage to suitably mount upon the terminal support 2 a mail box 68 of conventional form into which the postman may deposit the mail.

From the foregoing description, it is thought to be obvious that a device constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement

and formation of the several parts herein shown in carrying out my invention in practice.

I claim:

5. 1. A device of the character described including a hanger, a supporting wheel mounted on the hanger, a car connected with the hanger, a propeller carried by the hanger and capable of movement there-around, an operative connection between the propeller and the supporting wheel, and means carried by the hanger for controlling the connection between the supporting wheel and the propeller.
10. 2. A device of the character described including a hanger, a supporting wheel mounted on the hanger, a car connected with the hanger, a propeller carried by the hanger and capable of movement there-around, an operative connection between the propeller and the supporting wheel, and movable means carried by the hanger for controlling the connection between the supporting wheel and the propeller.
15. 3. A device of the character described including a hanger, a supporting wheel mounted on the hanger, a car connected with the hanger, a propeller carried by the hanger and capable of movement there-around, an operative connection between the propeller and the supporting wheel, a movable plate carried by the hanger provided with means for imparting endwise movement thereto, and means operated by the 20 movable plate for controlling the connection between the supporting wheel and the propeller.
25. 4. A device of the character described comprising a car, a hanger connected therewith, a supporting wheel mounted on the hanger, a sleeve rotatably engaged with the hanger, a tubular arm projecting from the sleeve, a shaft mounted in said tubular arm, an operative connection between the 30 shaft and the supporting wheel, and a propeller operatively mounted upon the shaft.
35. 5. A device of the character described comprising a car, a hanger connected therewith, a supporting wheel mounted on the hanger, a sleeve rotatably engaged with the hanger, a tubular arm projecting from the sleeve, a shaft mounted in said tubular arm, an operative connection between the shaft 40 and the supporting wheel, a propeller operatively mounted upon the shaft.

eratively mounted upon the shaft, and a 55 blade carried by the tubular arm.

6. A device of the character described comprising a car, a hanger operatively connected therewith, a supporting wheel carried by the hanger, a feathered propeller operatively supported by the hanger, an operative connection between the propeller and the supporting wheel, and means for reversing the hand of the propeller relative to its direction of rotation.

7. A device of the character described comprising a car, a hanger operatively connected therewith, a supporting wheel carried by the hanger, a feathered propeller operatively supported by the hanger, an operative connection between the propeller and the supporting wheel, and automatic means whereby the hand of the propeller may be adjusted relative to its direction of rotation.

8. A device of the character described comprising a car, a hanger carried thereby, a supporting wheel carried by the hanger, a shaft operatively supported by the hanger, a hub loosely mounted on the shaft, rods radiating from the hub, propeller blades swingingly mounted on the arms, manually operable means for reversing the hand of the blades relative to the direction of rotation of the hub, and means for operatively engaging the hub with the shaft.

9. A device of the character described comprising a car, a hanger connected thereto, a supporting wheel carried by the hanger, a shaft operatively supported by the hanger, a hub loosely mounted on the shaft, arms radiating from the hub, blades swingingly mounted upon the arms, a gear loosely mounted on the shaft and operatively engaged with the blades for swinging the same relative to the arms, a lever swingingly mounted upon the shaft, expandible connections between the lever and the gear, a clutch member slidable on the shaft and engageable with the lever, and means for imparting movement to the clutch member.

In testimony whereof I hereunto affix my signature in the presence of two witnesses.

WILLIAM E. FISHER.
